(No Model.)

W. W. DAVIS.
LOCK.

No. 529,606.

Patented Nov. 20, 1894.

UNITED STATES PATENT OFFICE.

WILLIAM W. DAVIS, OF EAST ORANGE, NEW JERSEY.

LOCK.

SPECIFICATION forming part of Letters Patent No. 529,606, dated November 20, 1894.

Application filed August 15, 1894. Serial No. 520,381. (No model.)

To all whom it may concern:

Be it known that I, WILLIAM W. DAVIS, of East Orange, in the county of Essex and State of New Jersey, have invented a new and 5 Improved Lock, of which the following is a full, clear, and exact description.

My invention relates to improvements in that class of door locks shown in Letters Patent of the United States, No. 521,366, dated 10 June 12, 1894, which shows the mechanism so arranged that when the door is open no parts of the lock will project in such a manner as to catch the person or clothing of people passing near.

15 The object of my present invention is to construct a lock having no protruding parts and also to improve the internal mechanism, to the end that the lock may be extremely positive in operation and little likely to get 20 out of order.

To these ends my invention consists of certain features of construction and combinations of parts, which will be hereinafter described and claimed.

25 Reference is to be had to the accompanying drawings, forming a part of this specification, in which similar figures of reference indicate corresponding parts in all the views.

Figure 1 is a broken sectional elevation of 30 the lock as applied to a door and frame, with the door in closed position. Fig. 2 is a sectional plan of the same. Fig. 3 is a detail sectional plan, showing the position of the parts as the door is about to close and actuate 35 the slide which is held in the keeper plate of the door frame, and which throws the latch into the lock case of the door. Fig. 4 is a detail rear elevation of the locking mechanism held in the keeper plate of the door frame; 40 and Fig. 5 is a detail perspective view of the slide and striking plate which are adapted to throw the latch into engagement with the lock case.

The lock is provided with a case 10 of substantially the usual kind, which is adapted to be countersunk in the door 11 in the usual way, and the door is arranged to swing in the ordinary manner against the stop head or facing strip 12 of the frame 13. The face plate 50 of the case 10 is provided with the usual bolt aperture 14 which, however, instead of containing the ordinary bolt is normally closed

by a swinging fly 15 which is pivoted at one edge, as shown at 16, and the free edge of which is adapted to swing in the recess 17 in 55 the lock case and door. The fly 15 is suitably pivoted between ears 10^a on the lock case and such ears are formed at both vertical edges of the opening 14 in order to permit of pivoting the fly 15 at either side of said opening to adapt the lock to a door swinging either way. The fly 15 is held closed, so that the lock case will present a perfectly smooth front, by a spiral spring 18 which is arranged to press upon the fly and is held upon a guide 60 rod or plunger 19 which moves between the guides 20 on the lock case, and the guide rod is secured to a slide plate 21 having a keeper 22 on one edge, which keeper slides on the upper guide 20 and the keeper receives the 65 head 23 of a guide rod 24, which is secured to the front edge of the lock and projects through the end of the keeper 22 which is pressed by a spring 25 encircling the guide rod 24, and the tension of the spring holds 70 the slide 21 in close contact with the follower 26 which is of exactly the usual kind and is fastened to the ordinary lock spindle 27 which is held in the lock and door in the ordinary way and provided with the usual knob 28. It 75 will thus be seen that by turning the knob in the ordinary manner the follower will be forced against the slide plate 21 so as to move it and carry the rod 19 against the fly 15 with sufficient force to close the fly and force out 80 the latch which is held in the fly opening, as will be described below.

The door frame 13 is provided, at a point opposite the lock case, with a keeper plate 29, which has an opening 30 in it opposite 90 the fly 15 of the lock, and in this opening is pivoted a latch 31 which has an outer flat face adapted to lie flush with the face of the keeper plate 29, the latch being pivoted between lugs 32 on the keeper plate and it has 95 a curved tail 33 adapted to fit a corresponding curved portion of the keeper plate, as shown best in Fig. 3, thus insuring an easy movement and a tight joint.

The latch 31 has on its inner or back side, 100 parallel cam wings 34, which are curved on both edges, the free edges being curved, as shown at 35, to fit the corresponding curved portion of the lugs 35^a which are secured to

or formed on the keeper plate 29, and these lugs carry a pin 36 at their inner ends, to which is secured a spring 37 and the spring is also secured to a pin 38 at the apices of the 5 curved or conoidal wings 34, and the spring thus serves to hold the latch 31 in either an open or closed position. When the latch is thrown outward, as will be hereinafter described, into the position shown in Fig. 2, so 10 as to enter the opening 14 in the lock case, the pressure of the spring 37 will hold the latch in the said locked position, and when the latch is closed, as shown in Fig. 3, the center of pressure from the spring is changed 15 and the spring serves to hold the latch in closed position.

Between the lugs 35^a, near the keeper plate 29, is a slideway 39 in which moves a slide block 40 which is secured to a striking block 20 41 placed at right angles to it, and this striking block has a thickened end 42 which is adapted to project beyond the stop bead or facing strip 12 parallel with the striking plate 29. The slide plate 40 carries a spring tongue 25 43 which extends between the wings 34 of the latch and terminates in a cross bar 44 adapted to ride on the curved back sides or edges of the wings 34, and consequently when the slide 30 40 is moved inward it pulls the cross bar 30 against the back edges of the wings 34 and forces the latch 31 outward. A spiral spring 43^a serves as an auxiliary to the spring 43, the former being connected to a lug 35^a and the striking block 41; also, the door 11 has 35 preferably a wear plate 11^a adapted for contact with the striking block.

The operation of the lock is as follows:— When the door is opened the fly 15 lies flush with the face plate of the lock case 10, and 40 the flat side of the latch 31 is flush with the face of the keeper plate 29. When the door is closed it strikes the thickened end 42 of the striking block 41 just before it reaches the shoulder 12, and the movement of the 45 striking block and slide plate 40 pulls on the cross bar 44 and forces out the latch 31 to a point when the spring 37 exerts a pressure against the latch 34 outward toward the fly, which fly is forced inward and, as soon as the 50 latch is fairly started, the change of position of the spring 37 causes the latter to push the latch well into the opening of the lock case, in which place it is securely held by the spring, so that the door is kept firmly closed 55 until the knob 28 is turned, when the rod 19 is forced against the fly 15 as above described, closing the fly and pushing in the latch 31 which is held by the spring 37, and then when the door is opened it presents a smooth edge 60 and the keeper plate 29 presents a smooth face.

Having thus described my invention, I claim as new and desire to secure by Letters Patent—

65 1. The combination, with the keeper plate having projections at its inner side, the swinging latch held in an opening of the keeper

plate, and the wings on the back of the latch, of the striking block projecting in front of the keeper plate, a spring tongue carried by 70 the striking block and engaging the backs of the said wings to force the latch outwardly, and a spring 43^a, substantially as described.

2. In a door lock, the combination with the case having an opening and pivot lugs at opposite sides thereof of the reversible fly 75 adapted to be pivoted to either of the lugs, the lock spindle and means for actuating the reversible fly from the spindle, substantially as described.

3. In a door lock, the combination with the lock case having an opening in the face plate, and the fly pivoted in the case and adapted to normally close the opening, of the lock 85 spindle, the follower thereon, the spring-pressed slide plate held against the follower, the guide rod carried by the slide plate and adapted to strike the fly, and a spring on the guide rod to press the fly, substantially as 90 described.

4. A door lock, comprising the usual case having an opening in the face plate, a fly hinged in the said opening, the usual lock spindle, means for closing the fly by the movement of the spindle, a keeper plate adapted 95 to be secured in the door frame, a swinging latch held in the keeper plate and adapted to swing into the lock case against the fly, and a spring secured to the latch and to an adjacent support and arranged to hold the 100 latch in either an open or closed position, substantially as described.

5. In a lock, the combination with the apertured keeper plate, of the spring-pressed latch hung in the plate and adapted to close the 105 aperture, the latch having a cam surface on its back, the movable striking block projecting adjacent to the keeper plate, and a cross bar carried by the striking block and adapted to engage the cam surface on the back of the 110 latch, substantially as described.

6. The combination, with the keeper plate, the swinging latch held in an opening of the keeper plate and the curved wings on the back of the latch, of the striking block projecting in front of the keeper plate, a tongue carried by the striking block, and a cross bar carried by the tongue and adapted to engage the backs of the wings, substantially as 115 described.

7. In a lock, the combination, with the keeper plate having an opening therein, the latch adapted to close the opening and provided with curved wings on its back, the spring arranged to hold the latch in either an 125 open or closed position, the striking block projecting in front of the keeper plate, a guide plate secured to the striking block and held to move in a slideway, a tongue carried by the striking block, and a cross bar carried by the 130 tongue and adapted to engage the wings on the latch back, substantially as described.

8. The combination with the door and frame, the lock case fastened in the door and

provided with an aperture and a fly held to close the aperture, an apertured keeper plate secured in the door frame, a latch adapted to close the aperture in the keeper plate and to swing inward against the fly in the lock case, a spring arranged to hold the latch in either an open or closed position, a striking block projecting into the path of the door, and

means for forcing out the latch by the movement of the striking block, substantially as described.

WILLIAM W. DAVIS.
